UNITED STATES PATENT OFFICE.

MARTIN W. STAPLETON, OF MUSCATINE, IOWA.

GRAVITY DRAIN.

Application filed October 20, 1921. Serial No. 508,910.

To all whom it may concern:

Be it known that I, MARTIN W. STAPLETON, a citizen of the United States, residing at Muscatine, in the county of Muscatine and State of Iowa, have invented certain new and useful Improvements in Gravity Drains; and I do declare the following to be a full, clear, and exact description of the invention, such as will enable others skilled in the art to which it appertains to make and use the same.

My invention relates to improvements in devices for draining damp and swampy land, and more particularly to a novel type of drain employing a hollow water collecting receiver to be inset in the earth, and a drain pipe leading from said receiver, preferably to the gravel and sand laden subsoil.

The principal object of the invention is to provide a drain of the class specified which may be easily and cheaply constructed, which may be applied to use by unskilled workmen, and which, regardless of these characteristics, will be efficient and reliable.

With the foregoing in view, the invention resides in the novel subject matter herein-after described and claimed, the descriptive matter being supplemented by the accompanying drawings:

Figure 1 is a side elevation of the invention showing one manner of applying the same to use.

Figure 2 is a vertical sectional view of the device shown in Fig. 1.

Figure 3 is a side elevation partly in section, showing a different form of construction.

Figure 4 is an enlarged vertical sectional view of the receiver and the upper section of the drain pipe.

Figures 5 and 6 are horizontal sectional views as indicated by lines 5—5 and 6—6 respectively of Fig. 4.

Figure 7 is a perspective view of one of the blocks of which the receiver wall is constructed.

In the drawings above briefly described, the numeral 1 indicates broadly a hollow receiver to be inset in the earth to collect water therefrom. This receiver may be constructed in numerous ways, but as here shown, it includes a horizontal rectangular bottom 2 preferably constructed of cement, concrete, or other porous material, said bottom being formed with an upright opening 3 which is preferably, though not necessarily, disposed

at its center, while on the upper side of said bottom, is a continuous upstanding rib 4, said rib being spaced inwardly from and in parallel relation with the edge of the bottom. 60

The rib 4 is loosely received in a continuous groove 5 in the lower edge of the lowermost section 6 of the upright receiver wall, the upper edge of said section having an additional continuous rib 7 received 65 loosely in a groove 8 formed in the lower edge of an upper wall section 9. The receiver wall may be formed only of the two sections 6 and 9 as shown in Figs. 1, 2 and 4, in which case a rectangular cap 10 rests on 70 the upper section 9, or the height of the wall in question may be increased by the application of one or more sections 9^a as shown in Fig. 3. It will also be understood that when the cap 10 is used, the wall may be built up 75 of any desired number of sections and when this cap is employed, the entire receiver 1 is adapted to be embedded in the earth to allow cultivation over the same without injury thereto, but when the cap is eliminated as in 80 Fig. 3, the open upper end of the receiver is adapted to be disposed on a level with the surface of the earth. When the last named arrangement is employed, moisture will not only permeate through the walls of the receiver, but surface water will run into said receiver, whereas when the cap 10 is used, moisture must soak through the walls of the receiver and leak through the several joints therein to effectively drain the soil. 85

Regardless of the manner in which the receiver 1 is used, the opening 3 in the bottom thereof loosely receives the upper end of an upright pipe section 11 with which a drain pipe 12 telescopes more or less, according to 90 conditions encountered when installing the invention. The upper end of the pipe section 11 is provided with a head 13 resting on the bottom 2. This head, in addition to supporting the pipe section 11, serves to trap 100 any sediment, silt and the like, which may enter the receiver 1 and to prevent this matter from being discharged through the drain pipe section 11. The matter in question, however, will gradually seep out of 105 the receiver between the upper portion of the pipe section 11 and the wall of the opening 3 and will thus drop into the upright hole 14 which is drilled in the earth and loosely receives the drain pipe when the invention is first applied to use. The continual discharge of silt and the like into the 110

hole 14, however, will in time fill the space surrounding the pipe 12 and will thus reliably anchor the same.

Although the drain 12 might well be formed of a single length of piping, it is preferably constructed of a number of porous tiles as illustrated in the drawings, and in most cases, it will lead from the receiver 1 to the gravel and sand laden subsoil, whereby any water collected by the receiver and discharged therefrom through the pipe, will be allowed to escape from the latter. However, it is obvious that under certain conditions, the pipe 12 might well communicate with a horizontal drain leading to any suitable point and forming no part of the present invention; therefore not shown. When tiles are used in the formation of the pipe 12, their bells are disposed downwardly so that while water is allowed to enter through the joints of the pipe, silt and the like is prevented from entering.

In the foregoing, I have described the continuous wall of the receiver as constructed of sections disposed one upon the other. In the embodiment shown, the several sections are each constructed of four L-shaped blocks 15 of cement or the like, each block having a long arm and a short arm, whereby the vertical joints of the sections may be disposed out of alignment as shown. Preferably, the joints between the several blocks 15 are in the form of loose-fitting tongue and groove connections, the longer arms of the blocks being provided with tongues 16 received loosely in upright grooves 17 formed in the short arms. These joints resemble the joints between the bottom 2 and the section 6 and between the superimposed sections, this style of joint being preferably used since it allows water to pass therethrough into the receiver. The horizontal groove 8 and any groove or grooves which may be located above the same, according to the number of superimposed sections of which the receiver is constructed, will collect mineral silts such as lime, magnesia, sulphur, alkali and also fine sand. If this matter were not given a chance to escape, it would clog the joints through which the water enters the receiver, but the vertical grooves 17 permit the silt and the like to run into the groove 5 from which it may gradually escape between the wall and bottom of the receiver.

Preferably, the cap or cover 10 is formed with a continuous groove 18 in its lower side

receiving the continuous rib 19 on the upper edge of the uppermost section of the receiver. The joint at this point may well be tight and may be supplemented by a continuous flange 20 depending from the edge of the cover into close contact with the outer side of the wall. However, although this feature of construction, as well as those previously described, is preferable, it is obvious that my invention is not restricted to such minor details and that within the scope of the appended claims, numerous minor changes may be made.

I claim:

1. A gravity drain comprising a receiver composed of a bottom, and a continuous upright wall rising therefrom and formed of a plurality of loosely jointed sections, and a drain pipe leading from the receiver.

2. A gravity drain comprising a hollow receiver having a continuous upright wall formed of contacting blocks having loose-fitting tongue and groove joints therebetween, and a drain pipe leading from said receiver.

3. A gravity drain comprising a hollow receiver including a bottom, an upright continuous wall rising therefrom and having a loose-fitting tongue and groove connection therewith, said wall being formed of contacting blocks having loose-fitting tongue and groove joints therebetween, and a drain pipe leading from the receiver.

4. A gravity drain comprising a hollow receiver including a bottom, an upright continuous wall rising therefrom and having a loose-fitting tongue and groove connection therewith, said wall being formed of contacting blocks having loose-fitting tongue and groove joints therebetween, a cover resting on the wall and closing the upper end of the receiver, and a drain pipe leading from said receiver.

5. A gravity drain comprising a hollow receiver adapted to be inserted in the earth to collect water therefrom, said receiver having a solid bottom provided with an opening, and a drain pipe passing through said opening in slightly spaced relation with its wall, said pipe having its upper end spaced above said bottom to collect silt in said receiver and permit it to seep out of the latter between said pipe and wall of said opening.

In testimony whereof I have hereunto set my hand.

MARTIN W. STAPLETON.
